ELECTRIC CONTACT PLUG

Donald E. Wadsworth, Bloomfield, N. J.

Application March 11, 1938, Serial No. 195,286

15 Claims. (Cl. 173—361)

This invention relates to electrical contact plugs and more particularly to a dual purpose plug adapted to be used as a screw-in plug wherein electrical connection is adapted to be made with a screw socket, for instance, and in other situations wherein electrical contact is adapted to be made by contact prongs.

It has heretofore been proposed to provide a dual purpose contact plug having a threaded 10 conductive shell for reception in the lamp socket and a contact centrally thereof for electrical connection with a center contact of the lamp socket, while at the same time having a pair of contact prongs adapted to enter and make electrical connection with the electrical contacts of 15 electrical connectors such as outlet fittings. In the dual purpose contact plug heretofore known, a member carrying the threaded conductive shell was reciprocable into and out of operative position but the center contact and the threaded shell were at all times in electrical connection 20 with the contact prongs, thereby affording a plurality of electrical contacts with the likelihood that certain of the contacts would be exposed 25 and create the danger of short circuit or electrical shock to the user. Moreover such prior dual purpose contact plug made no provision for retaining the parts in either operative position so that the device was, to all intents and purposes, 30 difficult to handle and manipulate.

One object of the present invention is a dual purpose plug of the character described having means to retain the respective parts in either position of adjustment.

Another object of the invention is a dual purpose contact plug in which the contacts not in use are not in the electrical circuit or are otherwise protected or insulated.

It is also an object of the present invention 40 to provide a dual purpose contact plug wherein the parts are retained against displacement in either selected condition of use.

The invention also seeks a dual purpose contact plug which is practical from the standpoint 45 of ease and cheapness of manufacture and durability and safety in use.

In one of its aspects, the invention has to do 50 with a dual purpose contact plug comprising a cup-shaped body member having spaced contact prongs carried therewithin and extending therewithout and upon which a threaded shell carrying member is reciprocable into and out of the body member, said threaded shell carrying member being formed with an axial bore into and

out of which a central contact member is adapted to reciprocate.

In accordance with another aspect of the invention, the dual purpose contact plug comprises a cup shaped body member having spaced contact prongs carried therewithin and a threaded shell carrying member reciprocable into and out of the cup-shaped body, the separation of the threaded shell carrying member and the body being prevented as by coacting stops on the respective members.

These and other objects of the invention and the means for their attainment will be more apparent from the following detailed description, taken in connection with the accompanying drawings illustrating one embodiment by which the invention may be realized, and in which:

Figure 1 is a view, in longitudinal section, showing the dual purpose plug of this invention with the parts disposed for reception in a lamp 20 socket;

Figure 2 is a fragmentary, longitudinal, sectional view taken in the same plane as Figure 1 but showing the central contact member with its parts in partially retracted position in the 25 threaded reciprocable plug member portion preparatory to these parts being withdrawn into the cup shaped body portion;

Figure 3 is a longitudinal, sectional view of the dual purpose plug taken in the same plane as 30 that of Figure 1 but with the parts in fully retracted position;

Figure 4 is a fragmentary, sectional view taken in the plane indicated by the line 4—4 of Figure 1 and looking in the direction of the arrows 35 and showing the instrumentalities by which separation of the body and threaded plug is prevented when the parts are in protracted position;

Figure 5 is a view showing the dual purpose plug of this invention with the parts in the 40 same position as that in Figure 1, but taken in a longitudinal plane perpendicular to the plane of Figure 1 and in the line 5—5 of that figure and looking in the direction of the arrows;

Figure 6 is a transverse, sectional view of the 45 central contact carrying member, taken in the plane indicated by the line 6—6 of Figure 5 and looking in the direction of the arrows;

Figure 7 is a longitudinal, sectional view of the dual purpose plug of this invention with the 50 parts in the same relative position as that shown in Figure 3 but taken in a plane perpendicular thereto along the line 7—7 of Figure 3 and looking in the direction of the arrows;

Figure 8 is a fragmentary, transverse, sectional 55

view showing the bottom of the cup shaped body member of this invention, taken in the plane indicated by the line 8—8 of Figure 1 and looking in the direction of the arrows;

5 Figure 9 is a top plan view looking down on the dual purpose plug of this invention with the parts in the position of Figures 3 and 7 and taken in the plane indicated by the line 9—9 of Figure 3, looking in the direction of the arrows, the contact prongs being in section;

10 Figure 10 is a side elevational view of the central contact carrying member as viewed in the plane indicated by the line 10—10 in Figure 1 and looking in the direction of the arrows; and

15 Figure 11 is a view showing the central contact member in elevation looking from the right as viewed in Figure 10, on the line 11—11 of that figure.

20 The dual purpose contact plug of this invention comprises generally a cup-shaped body member 15 of non-conductive material, such as a mouldable material, within which is mounted a pair of contact prongs 17, 19, extending longitudinally thereof and protruding a sufficient distance to permit them to be entered into and make electrical connection with the electrical contacts of electrical connectors, such as outlet fittings. Reciprocable into and out of the cup-shaped body member 15 is an insulatory member 21 carrying a threaded conductive shell 23 for reception in a lamp socket or the equivalent, and herein called the threaded shell member, and a contact carrying member 25 centrally thereof for electrical connection with a center contact of a lamp socket, the invention being generally so conceived and proportioned that when the dual purpose plug is to be used in connection with a lamp socket or the like, the contact prongs 17, 19 are concealed from view and insulated against all outside contact, while the threaded shell 23 and the central contact 27 are "live," they being in electrical connection with the electrical conductors to which the plug is attached. On the other hand, when this threaded shell 23 and central contact 27 are retracted into the body of the body 15, the threaded shell 23 and central contact 27 are rendered inoperative so that no electrical current is carried by them.

45 50 The lower end of the body member 15 is provided with a removable closure or cap 29 which conceals and protects the connections 31 with flexible electrical connectors.

55 Referring first to Figures 1 and 5, the dual purpose plug of this invention comprises preferably a one-piece body 15 formed with a preferably but not necessarily cylindrical bore 33 defined by the cylindrical wall 35 and an integral bottom 37. In its lowermost portion is a part 39 of reduced diameter which is conveniently threaded for the removable reception of a generally cup-shaped end member or cap 29 adapted to conceal the contact screws 31 by which electrical conductors, not shown, are secured in electrical connection 60 with the conductive parts of the plug and formed with an aperture 41 preferably centrally thereof through which the conductors may pass. As shown, the bottom of the cup-shaped member 35 is conveniently formed with spaced recesses or 65 grooves 43, conveniently diametrically opposite one another, in which the ends of the conductors, not shown, lie. The ends of the conductors may be further separated and insulated from one another by the downwardly projecting boss 45.

70 75 Mounted in the bottom 37, as by moulding or

other convenient manner of securement, are the two spaced contact prongs 17, 19, of usual conformation, generally speaking. At their lower ends, these contact prongs 17, 19 are each provided with a generally outwardly and somewhat downwardly extending end portion 47 lying within the aforesaid depressions or grooves 43 and tapped for reception of the contact screws 31 by which the ends of the electrical conductors are secured to the contact prongs for electrical connection therewith. Proximate these offset ends, ears 49 are, conveniently struck out from the prongs 17, 19 to lie in transverse planes thereof for reception in recesses 51 in the bottom 37 of the body, it being understood that these are conveniently secured in position in any convenient manner, as by moulding them therein during the formation of the cup-shaped body. The bottom 37 of the cup-shaped body 15 is also conveniently formed with recesses 53, one proximate the outer or remote surface of each prong 17, 19 for a purpose which will hereinafter be described and with generally longitudinally extending bores 55 for the reception of the respective threaded ends 57 of the securing screws 31 during their reciprocation. Conveniently the prong members extend outwardly of the mouth of the body member 15 a distance sufficient to function in making the usual electrical connection with the electrical contacts of electrical connectors such as outlet 25 fittings. Intermediate the inner and outer ends of the contact prongs, ears 63 are struck outwardly therefrom, as shown, to serve conveniently as stop members for preventing the separation of the shell member 21 from the body member 15 when the parts are in extended position. At some convenient point between the bottom of the concave body member and the positioning ears 63 aforesaid, the prongs 17, 19 are shown as recessed or grooved as at 65, serving 30 as one of a pair of latching instrumentalities retaining the parts in retracted position, as will be explained hereinafter more fully.

The threaded member 21 is also conveniently formed as a body 67 of non-conductive material, such as a moulded or mouldable composition. It is generally cylindrical and of such axial length as to abut against the flat bottom surface of the cup-shaped body member and lie wholly below the rim of the cylindrical wall 35 thereof, when 45 in retracted position. Conveniently secured to the outer periphery of this non-conductive plug member, is the threaded cylindrical shell 23 for reception in a lamp socket or the like. As shown, at its lower portion, the plug member 67 is of 50 slightly increased diameter, as at 69, and the shell member is grooved or otherwise formed with one or more indented portions 71 (Figure 5) to prevent axial and/or circumferential displacement of the shell with respect to the plug body. The 55 lower surface 73 of the threaded plug member 67 is flat, as shown, to seat on the generally flat bottom surface 75 of the cup interior. The upper or outer end of the threaded plug member 67 is concave as at 76, or dish-shaped and the upper 60 rim 77 of the threaded shell 23 is bent over and conveniently seated in or moulded within the concave surface so that the outer top surface of the shell is continuous with the end surface of the plug member.

The thread carrying plug member 67 is formed with an axial bore 79, conveniently, but not necessarily, of rectangular cross section and one pair of opposed walls 80, 80 of this bore is longitudinally grooved, preferably with a groove 81, 75

83 of T-shaped cross section, as shown in Figure 9, whereof the transverse main portion 81 of each groove receives the respective prongs 17 and 19 and the further inwardly directed portion 83 which permits the plug member 21 to move freely past the offset ears 63 of the prongs which may be received, respectively, in these groove portions. On a third side 85 of the rectangular bore, conveniently in a diametric longitudinal plane 10 perpendicular to the plane of the aforementioned grooves 81, 83, the wall of the bore is formed with a longitudinally extending groove 87 opening at its lower end in the lower surface of the reciprocable plug member, but extending upwardly 15 toward the other or concave upper end a distance short of the concave surface so that material of the plug forms a shoulder or stop 89, Figure 5, for the central contact carrying member 25.

In the central rectangular bore of the reciprocable plug member, reciprocates a central contact carrying member 25 illustrated in front and side elevation in Figures 10 and 11 and in top plan in Figure 9. This member rests within the rectangular bore with sufficient clearance for 20 freedom of movement. Its upper surface 86 is convex. It is conveniently formed of non-conductive material. At its upper end, on diametrically opposite sides, it is conveniently formed with recesses 91 of V-shaped longitudinal cross-section so that the ends 93 of a metallic plate 27 25 overlying and preferably embedded in at least the central portion of the convex top, as viewed in Figure 7, may be bent downwardly and under the downwardly inclined walls 97 of the recesses 30 91 to firmly position the metallic plate in position. This plate serves as the central contact. Conveniently the respective lower surfaces 99 of the recess are formed on a curve merging with the curve of the concave upper surface 76 of the 35 plug member 21 so as to facilitate engagement with, say, the thumb and finger thereby to grasp the contact carrying member and withdraw it from the threaded reciprocable plug 21 from the retracted position shown in Figure 7 to the protracted position shown in Figure 5.

In a plane transverse to the plane of the recesses or finger grips 91, the lower portion of one pair of sides of the contact member 25 is formed with recesses 101. The bottom of each recess is 50 defined by a transverse web portion 105 while the upper end of each recess is conveniently formed on the arc of a circle. The inner proximate surfaces of the recesses 101 become progressively deeper from the upper curved end to 55 ward the lower flat bottom end so that the longitudinal surfaces for an appreciable distance are inclined, as at 107, and then, for convenience in manufacture, the surfaces are parallel to one another, as at 109, down to the transverse web 105 60 which serves as the bottom of the central portion of the contact carrying member. Beneath the web 105 and extending in planes transverse to the plane of the recesses 101 and along the side edges of the central contact carrying member are downwardly depending flanges or side 65 walls 132 defining a transverse recess or groove for a leaf spring member 128, 131, hereinafter to be described. In the recesses 101 are pivotally carried insulatory stop members 111 which have 70 a normal tendency to be pressed outwardly from the grooves but which, when forced into the grooves, lie substantially wholly within the side walls of the central contact carrying member 25. As viewed in Figure 1, a leaf-spring-like conductive strip 113 extends downwardly from the con-

tact plate at one side thereof and with the contact plate is moulded into the material of the member so that it enters the slot at the curved upper end thereof inwardly of a side wall. The lower end of this conductive strip 113 is angularly 5 bent in an inward direction as at 115 and again bent downwardly, as at 117, to form a shoulder or latching recess which, as viewed in Figure 1, is adapted to engage the end of one contact prong, say, 17, to form electrical connection therewith 10 and retain the contact member 25 in extended position. The free portion 119 of this contact strip is embedded in the insulatory body 111 which is formed, at the upper end thereof, with a recess whereby some freedom of movement is 15 permitted of the contact strip. The shape of this member 111 is such as to afford insulation and reinforcement to the strip throughout substantially its entire length except at the shoulder which is exposed and the normal position of the same is 20 such that the contact strip has an inherent tendency to spring outwardly against the surface of the contact prong 17. At the lowermost portion on the outer side thereof, the insulatory body 111 is formed with a lug 121 shown as of semi-cylindrical shape which serves not only to space and insulate the strip from the contact prongs when the body is retracted into the plug, as shown in Figure 3, but this semi-cylindrical portion 121 is 25 of such form or shape as to be received in the 30 groove or recess 65 in the respective contact prongs 17, 19, as shown in Figure 3, to function as a spring pressed latch retaining the reciprocable threaded plug in the retracted position of Figure 3.

Diametrically opposite 119 a similar contact strip 123, which as before, is moulded within the interior of a body 111, as shown, and forms a second contact member for engagement with the end of the other contact prong. Here again the 40 shape and function of the device and its reinforcing and insulatory enclosing body is the same as that described and like reference characters are used throughout. Joined with this contact strip 123, within the body of the contact carrying 45 member 25, is the upper end 125 of a leaf spring also formed therewithin during the process of manufacture, as shown in Figure 5, which extends downwardly within the body and then outwardly around a boss 127 moulded integral with 50 the body, as shown, and then inwardly as at 128 to be movable in the open ended transverse groove 129 formed in the bottom end of the member 25. This spring member is then reversely bent, as at 55 131, beneath the bottom of the member and when compressed (Figure 7) the parts 128, 131 lie within the transverse groove 129 which is shown as formed by the two depending walls 132 beneath the web 105 there shown. The bottom portion 133 of this spring member extends downwardly 60 and outwardly and is received within a slot 135 formed in the wall of the reciprocable threaded shell carrying member 67 with its end portion 137 in electrical connection with the conductive shell 23. 65

It will be observed from an inspection of Figures 1 and 5 that the electrical connection may be made from the central contact 27 to the contact prong 17 through the leaf spring 119 on the one hand and from the shell 23 through the re-tracting spring 125, 131 and the other leaf spring 123 to the other contact prong 19. The re-tracting leaf spring has another function. It is so shaped in manufacture as to normally assume the position shown in Figure 7, with the arms 70 75

128 and 131 proximate and when the central contact carrying member 25 is in its extended position, as shown in Figure 1, the spring is under tension and so soon as the two latching members 5 111 are drawn together into the opposed slots 101, so that they are free, inwardly, of the ends of the prongs, the leaf spring has a tendency to draw this central member downwardly to its innermost position as shown in Figure 3 and retain it in that position.

To prevent separation of the parts, that is the body 15 and shell member 21, companion stop members are carried with the shell member 21. These are shown as U-shaped members, seen in 15 side elevation in Figure 4. The arms 141 of the U are spaced a distance sufficient to receive therebetween the struck out lugs 63 on the prongs 17, 19. The upper ends of the arms 141 are bent outwardly and downwardly as shown 20 at 143 for reception in recesses 145 in the side walls of the longitudinal grooves 81 and 83. These arms have some degree of inherent resiliency so that they may be easily inserted and snapped into place in the recesses 145 during 25 assembly, if desired.

The operation of the device will be apparent from the foregoing description. Assuming the parts of the dual purpose plug in the position of Figures 3 and 7, the parts will be retained in that 30 position by reason of the fact that the central contact carrying member is retained in fixed retracted position within the body by virtue of the entrance of the latching lugs 121 within the recesses 65 in the prongs. Relative movement 35 between the threaded shell carrying member 21 and the central contact carrying member 25 is prevented at this time by the latching means 121, 65. It will also be apparent that, irrespective of the latching means 121, 65, the contractile tendency of spring 128, 131 tends to draw the central contact member 25 downwardly into the bore of the member 21 and tends to hold it there. The spring 128, 131 may also be utilized as a limiting stop for the member 25 in its lowermost position. Thus, that portion 134 of the spring leaf 40 128 under the boss 127 abuts, under the influence of the spring, the portion 137 of the spring leaf 131. At this time, the central contact member is not in electrical connection with the prongs so 45 that in no circumstances can the central contact cause a short circuit or offer an exposed surface which might give rise to shock to the user or a spark to some other conductive part. Again the threaded shell 23 is similarly out of electrical connection with the contact making screws 31 by 50 reason of the fact that the conductive spring 128-131 is out of electrical connection with the contact prong by reason of the fact that the leaf spring contact member 123 is retained in spaced position from the prong and is insulated therefrom. Further the material of the central contact carrying member insulates the two leaf spring contacts 119 and 123 from one another 55 and when these contacts are within the recesses 60 of the member, they are completely insulated and all contact with outside conductive surfaces is prevented.

To change the relation of parts and render the shell carrying member operative, it is merely 65 necessary to reach within the prongs with the thumb and forefinger and grasp the member 25 by the opposed recesses 91. Withdrawal of the member 25 brings with it the shell carrying member 21. That member is stopped in operative position by the interconnection of the stops 70 75

63 and 141. The central contact member may be further moved to extended or final stop position when stops 89 and 127 engage, this being permitted by the yielding characteristics of the conductive spring 128-131 until the central contact 5 27 is in operative position when the leaf spring contacts 119 and 123 have reached the point where they can snap outwardly, due to their inherent resiliency, over the ends of and in electrical contact with the contact prongs 17-19. 10 The parts are then in position to function as a screw-in plug for electrical connection with a screw socket or other similar device.

The parts are thus fixedly retained in this position. Relative rotation of the threaded shell 15 with respect to the prongs is prevented and the structure is sufficiently rigid and any loose-play prevented by the spring action of the several parts, so that there is no tendency for the parts to wobble or to collapse into the interior of the 20 body.

To restore the parts to the original position of Figure 3, it is merely necessary to press the insulatory members 111 toward one another by a pinching action of the thumb and forefinger. 25 Should the prongs be connected with a source of electrical current at that time, the fingers are nevertheless insulated from the conductive strips by the enclosing insulation 111. Collapsing the contact strips as described throws the central 30 contact out of circuit and downward pressure thereon will force the central contact carrying member downwardly within the shell carrying member 21. Of course, the shell is similarly out of circuit and can be safely handled also. Continued pressure on the central contact member 25 forces both members downwardly into the interior of the body member 15 where they are retained and latched in position as before.

Various modifications will occur to those skilled 40 in the art in the composition, configuration and disposition of the component elements going to make up the invention as a whole as well as in the selection of features for use in other combinations and no limitation is intended by the 45 phraseology of the foregoing description or illustrations in the accompanying drawings, except as indicated in the appended claims.

What is claimed is:

1. A dual purpose contact plug comprising a 50 cup-shaped body member, spaced contact prongs carried therewithin and extending therewithout, a threaded shell carrying member formed with a bore and reciprocable into and out of the body, a threaded shell carried by said last named member for electrical engagement with the threaded contact in a socket, a central contact member reciprocable into and out of the bore in the shell carrying member from a protracted position without the bore to a retracted position within the bore and a central contact carried by said contact member for electrical contact with a central contact in a socket in protracted position. 55

2. A dual purpose contact plug comprising a cup-shaped body member, spaced contact prongs 60 carried therewithin and extending therewithout, a threaded shell carrying member formed with a bore and reciprocable into and out of the body, a threaded shell carried by said last named member for electrical engagement with the threaded 65 contact in a socket, a central contact member reciprocable into and out of the bore in the shell carrying member from a protracted position without the bore to a retracted position within the bore, a central contact carried by said contact member for electrical contact with a central contact in a socket in protracted position. 70

75

tact member for electrical contact with a central contact in a socket in protracted position and means normally retracting the central contact member into the bore.

5 3. A dual purpose contact plug comprising a cup-shaped body member, spaced contact prongs carried therewithin and extending therewithout, a threaded shell carrying member formed with a bore and reciprocable into the body to expose the 10 prongs for insertion in a receptacle and out of the body to conceal and render impossible the insertion of the prongs in a receptacle, a threaded shell carried by said last named member for electrical engagement with the threaded contact 15 15 in a socket, a central contact carrying member reciprocable into and out of the bore in the shell carrying member from a protracted position without the bore to a retracted position within the bore, a central contact carried by said contact member for electrical contact with a central contact in a socket in protracted position, means to prevent separation of the threaded shell carrying member and the body member comprising a recess in a contact prong and a coating extensible stop carried with the central contact carrying member and operative connections preventing separation of the shell carrying member and the central contact carrying member.

20 4. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and formed to receive the prongs, a threaded shell carried by the intermediate member, an end member of a cross-sectional area to be received in the intermediate member, a central contact carried by the end member, a movable conductive member carried by the end member and electrically connected with the shell and adapted to overlie a prong and make electrical contact therewith in protracted position of the end member.

25 5. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell carried by said intermediate member, an end member of a cross-sectional area to enter the intermediate member, a central contact carried 30 by the end member and a movable conductive member carried by the end member and electrically connected with the central contact and adapted to overlie the end of a prong in protracted position of the parts to complete the circuit with a prong.

35 6. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell contact carried by said tubular intermediate member, an end member of a cross-sectional area to enter the intermediate member, a central contact carried by the end member and a conductive resilient member electrically connected with each contact and adapted to overlie the end of a prong in protracted position of the 40

end member to retain the members in protracted position.

7. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell contact carried by said intermediate member, an end member of a cross-sectional area to enter the intermediate member, a central contact carried by the end member and a conductive resilient member electrically connected with one of said contacts and carried by the end member and adapted to overlie the end of a prong in protracted position of the parts, said central contact carrying member being formed with a recess to receive the conductive resilient member in retracted position of the parts, and dielectric material carried by said conductive resilient member to insulate said member from a prong in retracted position.

8. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell contact carried by said intermediate member, an end member of a cross-sectional area to enter the intermediate member, a central contact carried by the end member and a yielding conductive member electrically connected with each contact and adapted to overlie the end of a respective prong in protracted position of the parts and insulating means carried by each resilient member.

9. A dual purpose contact plug comprising a cup-shaped body member of insulatory material, spaced contact prongs carried therewithin and extending therewithout, a member carrying a conductive threaded shell and formed with a bore and reciprocable into and out of the body, a central contact carrying member reciprocable into and out of the bore in the shell carrying member, resilient conductive retracting means tending to normally retract the central contact member into the bore in the threaded shell member, said resilient means being in electrical connection with the threaded shell and resilient conductive means in electrical connection with said resilient retracting means and adapted to make electrical connection with a contact prong.

45 10. A dual purpose contact plug comprising a cup-shaped body member of insulatory material, spaced contact prongs carried therewithin and extending therewithout, a member carrying a conductive threaded shell and formed with a bore and reciprocable into and out of the body, a central contact carrying member reciprocable into and out of the bore in the shell carrying member, resilient conductive retracting means tending to normally retract the central contact member into the bore in the threaded shell member, said resilient means being in electrical connection with the threaded shell and resilient conductive means in electrical connection with said resilient retracting means and adapted to make electrical connection with a contact prong, said last named resilient conductive means normally preventing retraction of the central contact carrying member into the bore in the threaded shell carrying member.

11. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell carried by said intermediate member, an end member of a cross-sectional area to enter the intermediate member, a central contact carried by the end member and a yielding latch member carried by the end member and adapted to overlie the end of a prong in protracted position of the parts to retain the end member in protracted position. 5
12. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a contact carried by said intermediate member, an end member of a cross-sectional area to enter the intermediate member, a contact carried by the end member and a movable conductive member carried by the end member and electrically connected with one of said contacts and adapted to overlie the end of a prong in protracted position of the parts to complete the circuit with a prong. 10
13. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and formed to receive the prongs, a threaded shell carried by the intermediate member, an end member of a cross-sectional area 15 to be received in the tubular member, a central contact carried by the end member, a conductive tension member between the intermediate member and the end member and in electrical connection with the shell and having a portion adapted to overlie a prong and make electrical contact therewith in protracted position of the end and intermediate members. 15
14. In a dual purpose electrical contact plug, in combination, a hollow cup-shaped body member, two spaced substantially parallel conductive contact prongs secured in the body member and extending therewithout, a tubular intermediate member of a cross-sectional area to enter the body member and receiving the prongs, a threaded shell carried by said tubular member, an end member of a cross-sectional area to enter the intermediate member, a central contact carried by the end member, yielding conductive latch members carried by the end member and adapted to respectively overlie the prongs in protracted position of the parts, a conductive connection between the central contact and a latch member 20 and a conductive expansible connection between the threaded shell and the other latch member urging the end member to retracted position. 20
15. In a dual purpose electrical contact plug, in combination, a hollow cup-shaped body member, two spaced substantially parallel conductive contact prongs secured in the body member, a tubular threaded shell carrying member of a cross-sectional area to enter the body member and receiving the prongs, a threaded shell carried by 25 said cylindrical member, a central contact carrying member of a cross-sectional area to enter the shell carrying member, a stop carried by the shell carrying member, a stop carried by a prong engaged by the first named stop in protracted position of the parts to limit outward movement thereof and a conductive resilient member carried by the central contact member and adapted to overlie the end of a prong in protracted position of the parts. 30 35
